United States Patent Office.

R. D. McDONALD, OF JERSEY CITY, NEW JERSEY.

Letters Patent No. 95,030, dated September 21, 1869.

FIRE-PLACE.

The Schedule referred to in these Letters Patent and making part of the same.

To all whom it may concern:

Be it known that I, R. D. McDONALD, of Jersey City, in the county of Hudson, and State of New Jersey, have invented a new and improved Fire-Place Heater; and I do hereby declare that the following is a full, clear, and exact description thereof, which will enable others skilled in the art to make and use the same, reference being had to the accompanying drawing, forming part of this specification.

The figure is a detail sectional view of my improved heater.

This invention has for its object to furnish an improved open-grate fire-place heater, which shall be so constructed and arranged as to utilize the heat that usually escapes into the chimney, so as to economize fuel, and obtain the advantages of a stove and open fire; and

It consists in the construction of the heater, as hereinafter more fully described.

The heater may be made of cast or sheet-metal, as may be desired or convenient, and of any desired size, according to the size of the room in which it is to be placed. The grate that supports the fire may be made and secured in place in the ordinary manner.

At the ends of the grate are formed openings A, leading into the vertical flues B, which extend up at the sides of the fire-place, as shown in the figure.

Directly over the middle part of the fire is formed another opening, C, leading into the lower horizontal flue D, into which open the upper ends of the flues B,

and which, at one end, opens into one end of the upper horizontal flue E the other end of which communicates with the chimney-flue F, as shown in the figure.

By this construction and arrangement of the flues, the heat will be almost entirely withdrawn from the products of combustion, and radiated into the room by the metallic walls of the said flues, as the said products of combustion are passing through them.

The openings A and C should be provided with dampers, so that the draught, and consequently the distribution of the heat, may be regulated at will.

When made of cast-metal, the heater may be cast in one or more pieces, as may be desired or convenient.

Upon the top wall of the heater should be laid two or more courses of bricks, to receive the mantel, so that the said mantel may not be unduly heated.

Having thus described my invention,

What I claim as new, and desire to secure by Letters Patent, is—

The combination and arrangement of the flues B D E, and openings A C, in a fire-place heater, made of cast or sheet-metal, substantially as herein shown and described, and for the purpose set forth.

R. D. McDONALD.
